UNITED STATES PATENT OFFICE

115,218

DESIGN FOR A DISPENSER FOR POWDERED SOAP OR THE LIKE

George H. Packwood, Jr., St. Louis, Mo.

Application October 28, 1938, Serial No. 80,730

Term of patent 14 years

To all whom it may concern:

Be it known that I, George H. Packwood, Jr., a citizen of the United States, residing at St. Louis, State of Missouri, have invented a new, original, and ornamental Design for a Dispenser for Powdered Soap or the like, of which the following is a specification, reference being had to the accompanying drawing, forming a part thereof in which:

Fig. 1 is a plan view of the dispenser for powdered soap or the like showing my new design;

Fig. 2 is a side elevation;

Fig. 3 is a bottom view; and,

Fig. 4 is a front view.

The dominant features of the invention reside in the shapes of the handle and the bracket and the disposition of the handle and the bracket with respect to the bowl, as shown.

What is claimed is:

The ornamental design for a dispenser for powdered soap or the like, as shown and described.

GEORGE H. PACKWOOD, JR.
